UNITED STATES PATENT OFFICE.

SAMUEL EDWARD JOHNSTON, OF DELTA, COLORADO.

INSTEP AND ANKLE SUPPORT FOR SHOES.

1,142,713.

Specification of Letters Patent. Patented June 8, 1915.

Application filed April 4, 1913, Serial No. 758,873. Renewed November 3, 1914. Serial No. 870,169.

To all whom it may concern:

Be it known that I, SAMUEL EDWARD JOHNSTON, a citizen of the United States, residing at Delta, in the county of Delta and State of Colorado, have invented certain new and useful Improvements in Instep and Ankle Supports for Shoes; and I do hereby declare the following to be a full, clear, and exact description of the invention, such as will enable others skilled in the art to which it appertains to make and use the same.

This invention relates broadly to boots and shoes, and has particular reference to instep arch and ankle supports.

As its principal object, this invention aims to provide a stiffening counter for shoes, formed with such regard to proportion and arrangement of parts that the device performs the dual function of preserving the desired shape of the shoe and acting as an instep arch and ankle support.

A further object of this invention is to provide a device of the character above described, which may be cheaply manufactured, readily attached to any shoe, and will be durable and efficient in the performance of its function.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and through the several views of which similar reference numerals designate corresponding parts: Figure 1 is a longitudinal section taken through a shoe equipped with this invention; Fig. 2 is a top plan view of the counter support in disassembled position; Fig. 3 is a section on the line 3-3 of Fig. 1; and Fig. 4 is a detail view of one of the heel taps.

Proceeding now to the description of the drawings, the preferred embodiment of this invention includes a counter designated as an entirety in Fig. 1, by the numeral 1, arranged within a shoe A in the usual position, with the heel portion of the counter abutting the heel wall of the shoe. This counter member 1 is preferably formed of some resilient or yielding metal, such as thin spring steel, although any suitable and desirable

fibrous material, which will give the desired stiffness for preserving the shape of the shoe and for supporting the arch and ankle, may be employed. The counter member includes a side wall 2 and heel plate 3, from the forward end of which extends an integrally formed tread tongue 4. The side wall 2 is of the customary structure at the rear rounded portion, but differs from the ordinary counter in that it is extended on each side to a considerable distance beyond the heel 5 of the shoe, terminating at a point approximately at the junction of the arch and tread of the shoe. These terminal portions 6 and 7 of the side wall 2 are curved inwardly in such manner as to conform to the cheeks or sizes of the arch of the wearer's foot, being thus fastened to serve as an effectual support for the arch. In this connection, it will be noted, the tread tongue 4 forms a still further support for the bottom of the foot, particularly for that part adjacent the ball of the foot. It is also to be observed that, by shaping the heel portion of the counter in the manner illustrated in the drawings, an effectual bracing is provided for the wearer's ankle, by reason of the fact that the shifting and turning of the heel in the shoe is prevented by the semi-rigidity of the material of which the counter is formed. This counter is not intended to replace the customary steel shank provided in the shank of most shoes, but is designed solely as an arch and ankle supporting counter. In holding the counter in the desired position in the shoe, this invention employs a plurality of bolt members 8, the heads 9 of which are counter sunk in the member 3 of the counter, the screw threaded shank of the bolts being seated in suitable bores provided in the heel and threaded into the burs or nuts 10 embedded in the heel, in a manner to be disclosed. In seating the nuts 10 in the heel, and as a means for holding them against rotation, one of the heel lifts, as indicated at 11, in Fig. 4, is provided with squared apertures 12 of such size that they will permit the members 10 to be snugly inserted, but will act to prevent the rotation of the nuts. 105

In building the heel, the tap 11 is placed approximately midway the depth of the heel, and the nut members are then inserted, being arranged in registration with the bolt receiving bores formed in the upper heel lifts. The remaining lifts 13 are then attached in the usual manner, thus embedding

the nuts 10 within the heel and holding them in the desired position for receiving the bolt shanks, at the same time concealing them from observation.

5 In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion and arrangement of parts may 10 be resorted to, when required, without sacrificing any of the advantages of my invention, as defined in the appended claim.

What is claimed is:

15 The herein described combined counter and arch support for boots and shoes made 20

from a single piece of sheet metal and comprising a counter portion having an integral sole portion adapted to cover the entire heel of the shoe on the inside thereof, said sole portion being curved to conform to the 25 upper surface of the arch of the shoe, said counter portion extending around the heel and forwardly at the sides to a point some distance beyond the breast of the heel over the arch of the shoe, and an integral tongue 30 terminating at a point substantially coincident with the forward end of the arch of the shoe.

In testimony whereof I affix my signature in presence of two witnesses.

SAMUEL EDWARD JOHNSTON.
